ROTARY ACTUATORS

Gerald H. Leland, Dayton, Ohio, and Oliver F. Davis, deceased, late of Dayton, Ohio, by Mary A. Davis, executrix, Dayton, Ohio, assignors to Ledex, Inc., a corporation of Ohio

Filed Sept. 21, 1959, Ser. No. 841,053

2 Claims. (Cl. 74—89)

This invention relates to rotary actuators and more particularly to a fluid powered device for imparting reciprocatory rotary motion to an output shaft, however the invention is not necessarily so limited.

The present application constitutes a continuation-in-part of the copending application Serial No. 726,942, filed April 7, 1958, and now abandoned, by Gerald H. Leland and Oliver F. Davis for a Rotary Actuator. This copending application discloses a rotary actuator which is powered by fluid under pressure and which is characterized by a rotary output stroke which is large in relation to the linear fluid displacement in the actuator. A noteworthy feature of this device is that it is small and compact in view of the power transmitted. The present invention is the result of efforts to improve and simplify the construction of this device, particularly the means with which the propelling fluid is contained within the device.

An object of the present invention is to provide an improved fluid receiving chamber construction for a fluid powered rotary actuator.

Another object of this invention is to provide an improved thrust plate construction for use in fluid powered rotary actuators wherein fluid power is transformed to mechanical power through the medium of a flexible diaphragm operating on the thrust plate, the thrust plate being dual-functional in that it transmits mechanical power while simultaneously providing support for one end of a rotary output shaft. This construction offers the benefit that the rotary output shaft need not project into or through the fluid receiving chamber, thus obviating the need for rotary fluid seals.

Another object of the present invention is to provide an improved thrust bearing design embodying a trapping cage for the bearing elements.

Other objects and advantages reside in the construction of parts, the combination thereof, the method of manufacture and the mode of operation, as will become more apparent from the following description.

In the drawing, FIGURE 1 is a longitudinal sectional view of a fluid powered rotary actuator constructed in accordance with this invention.

FIGURE 2 is a sectional view taken substantially along the line 2—2 of FIGURE 1 and drawn to reduced scale.

FIGURE 3 is a sectional view taken substantially along the line 3—3 of FIGURE 1 and drawn to reduced scale.

FIGURE 4 is a sectional view analogous to that of FIGURE 3 illustrating another position for the rotary actuator.

FIGURE 5 is a longitudinal sectional view of the modification.

Referring to the drawing in greater detail, the rotary actuator of this invention is enclosed in a generally cylindrical housing 10 which is formed with a circular base 12 press-fitted within a generally cylindrical sleeve 14. Threaded mounting studs 16 are press-fitted in the base 12.

Opposite the base 12, the sleeve 14 is closed with a generally circular cap 18 secured to the sleeve 14 by means of bolts 20. Interposed between the sleeve 14 and the cap 18 is a flexible elastomeric diaphragm 22. A fluid seal between the sleeve 14 and the cap 18 is effected by compression of the outer margin of the diaphragm 22 upon tightening of the bolts 20. In effect, the diaphragm 22 divides the interior of the housing 10 into two cham-

2

bers. One chamber adjacent the cap 18 serves as a fluid receiving chamber and communication thereto is afforded by an internally threaded port 24 in the cap 18. The other chamber, which is opposite the cap 18, houses a mechanism for converting axial movement of the diaphragm to rotary movement of an output shaft 26.

The output shaft 26 is supported for rotation at the geometric axis for the housing 10 by means of a sleeve bearing 28 press-fitted in the base 12. The inner end of the shaft 26 is rotatably received by a socket 30 integral with a generally circular thrust plate 32 positioned adjacent the diaphragm 22. For simplicity of manufacture, the thrust plate 32 and the bearing 28 are formed of a suitable plastic material, such as sintered nylon, which has a low coefficient of friction in contact with metallic surfaces. It is to be understood, of course, that other plastics may be used and that these parts may also be fabricated from metals. The thrust plate snugly fits the wall of the sleeve 14 so as to contain the diaphragm.

Axial movement of the thrust plate 32 is transmitted to a rotary conversion mechanism, to be described later, by means of a thrust bearing formed with ball elements 34. Interposed between the ball elements 34 and the adjacent surface of the thrust plate 32 is an annular reinforcing ring 36 which distributes the contact pressure with the ball elements 34 over a large area of the thrust plate. The ball elements 34 bear against a metallic thrust receiving plate 38 and are secured adjacent this plate by means of a caging member 40. This caging member is provided with suitable apertures 41 through which the ball elements 34 project partially, the diameter of these apertures being less than the diameter of the ball elements 34. This caging member is secured with rotational freedom to the thrust receiving plate 38 with fingers 42 struck from the periphery thereof so as to hook around outwardly projecting shoulders 44 provided in the periphery of the thrust receiving plate 38. The length of these fingers 42 is such that the ball elements 34 cannot escape their apertures 41 and hence are trapped between the caging member 40 and the thrust receiving plate 38. The fingers 42 are long enough, however, that there is some play in the caging member 40, the construction being such that the trapping action of the caging member does not interfere with the normal function of the ball elements 34.

The thrust receiving plate 38 is maintained in intimate contact with a companion plate 46 by means of a central keeper 48 surrounding the shaft 26. This keeper 48 has outwardly projecting shoulders 50 and 52 which retain the plates 38 and 46 in fixed relation. The plate 46 is one plate of a rotary conversion mechanism which includes a coaxial annular plate 54 and intermediate ball elements 58. The coaxial plate 54 is secured fixedly to the base 12 by means of studs 56.

With particular reference to FIGURES 3 and 4, it will be observed that the coaxial plates 46 and 54 are provided with oppositely inclined recesses 60 and 62 respectively. In the preferred design, each plate has three such recesses spaced 120 degrees apart, the recesses following an arcuate path concentric to the axis of rotation of the shaft 26. One ball element 58 is interposed between each pair of opposing recesses 60 and 62. When the coaxial plates 46 and 54 are aligned as in FIGURE 4, so that the ball elements 58 are in the shallow ends of the opposing recesses, an axial thrust driving the plates one toward the other will urge the ball elements to move to the deep ends of the recesses thereby urging relative rotation of the plates 46 and 54. The plate 54 being anchored to the base 12, it is the plate 46 which is urged to rotate.

The rotary torque on the plate 46 is transmitted to the shaft 26 by means of a spline formed with generally rectangular key inserts 66. With reference to FIGURE

2, these key inserts 66 are seated in notches 64 provided in the shaft 26, each of the inserts 66 having a width which exceeds slightly the diameter of the shaft 26. To accommodate the key inserts 66, the keeper 48 is provided with a rectangular central aperture 68 the width of which corresponds to the width of the key inserts, and the height of which corresponds to the distance between the outer surfaces of the key inserts. Through this construction, the key inserts cooperate to couple the keeper 48 non-rotatably to the shaft 26 and serve as bearings for sliding axial movement of the keeper. For this purpose, the key inserts are fabricated from a material which has a low coefficient of friction in contact with the metal of the keeper. This material may be sintered nylon, for example. To insure efficient torque transmission between the plate 46 and the keeper 48, it may be desirable to weld the plate 46 to the keeper 48. However, in many applications, it suffices if the plates 38 and 46 are compressed snugly between the shoulders 50 and 52 of the keeper.

With reference to FIGURE 1, it will be observed that the key inserts 66 project outwardly of the shaft 26 beyond the diameter of the adjacent bearing 28. To secure the shaft 26 against axial movement relative to the housing 10, a retaining ring 70 is seated in a suitable receiving groove 72 in the shaft 26 adjacent the outer wall of the base 12. The retaining ring 70 in cooperation with the key inserts 66 secure the shaft 26 against axial movement.

In rotary actuators of this type it is found preferable to preload the ball elements 58 in the rotary conversion mechanism. To accomplish this, a coil spring 74 is interposed between the keeper 48 and the thrust plate 32. This spring 74 functions to collapse the fluid receiving chamber when not under pressure while simultaneously maintaining a slight bias on the rotary conversion mechanism.

In operation, the rotary actuator of FIGURE 1 is connected to any suitable biasing mechanism, not shown, which will bias the shaft 26 rotatably so as to urge the plate 46 to the position illustrated in FIGURE 4. This sets the rotary conversion mechanism so that an axial thrust delivered by the diaphragm 22 will produce rotary motion of the shaft 26. The biasing mechanism may comprise a coil spring, as one example, or the biasing force may exist inherently in mechanism which is to be operated by the rotary actuator.

The modification illustrated in FIGURE 5 is equipped with its own biasing mechanism. This modified rotary actuator is assembled within the housing 80 formed of a circular base 82 press-fitted into a generally cylindrical sleeve 84. Suitable threaded mounting studs 83 are provided in the base 82.

Opposite the base 82, the sleeve 84 is closed by a cap 86 secured with bolts 88. The outer margin of a partitioning diaphragm 90 is clamped between the cap 86 and the sleeve 84. Access to the left of the diaphragm 90 as viewed in FIGURE 5 is afforded by means of an internally threaded port 92 formed in the cap 86.

Axial thrust of the diaphragm 90 resulting from fluid pressure transmitted through the port 92 is delivered to a thrust plate 94 adjacent the diaphragm. Axial movement of the thrust plate 94 is utilized to rotate a shaft 100 which is supported for rotation at the geometric axis of the housing 80 by means of a sleeve bearing 102 press-fitted in the base 82 and by means of a socket 104 located in the thrust plate 94. As is the case with the preferred embodiment, it is found advantageous to construct the bearing 102 and the thrust plate 94 from a plastic material such as sintered nylon; however, it is recognized that other materials may be used satisfactorily.

A rotational torque is obtained with coating plates 106 and 108 separated by ball elements 110. The construction of these members substantially duplicates the

construction of the coating plates 46 and 54 of the preferred embodiment. The plate 108 is secured fixedly to the base 82 by means of screws 112. The plate 106 is fixedly secured to a central hub 114 which is mounted for sliding axial movement on the shaft 100. Axial thrust of the diaphragm 90 is transmitted to the plate 106 by means of ball elements 116 forming a thrust bearing between the thrust plate 94 and a thrust receiving spacer plate 118 mounted on the hub 114 adjacent the plate 106. A reenforcing plate 98 backing up the thrust plate 94 assists in distributing the thrust load over the thrust plate. A shim 96 interposed between the reenforcing plate 98 and the diaphragm 90 functions to prevent extrusion of the diaphragm around the thrust plate 94. For this purpose the shim 96 is dimensioned to fit snugly within the sleeve 84.

As with the preferred embodiment, transmission of rotational torque to the shaft 100 is facilitated through the use of key inserts 120 fitted in suitable notches 122 20 in diametrically disposed positions in the shaft 100. Complementary to the key inserts 120, the hub 114 has a rectangular central aperture.

An annular retaining ring 124 seated within a suitable groove in the shaft 100 cooperates with the key inserts 120 and the bearing 102 to secure the shaft 100 against axial movement.

A bias effective to set the plates 106 and 108 to the correct position for delivering a rotational torque to the shaft 100 is obtained by means of a coil spring 126 secured at its inner end in a notch 128 in the shaft 100 and secured at its outer end to a plate 130. This plate is anchored to the outside surface of the base 82 by means of nuts 32 threaded onto the mounting studs 83.

In operation, fluid under pressure is permitted to flow 35 through the port 92 to the left side of the diaphragm as viewed in FIGURE 5. The axial thrust upon the diaphragm is transmitted to the plate 106 by means of the bearing elements 116. In response to this axial thrust, the ball elements 110 induce the plate 106 to rotate relative to the plate 108 thus rotating the shaft 100. As the shaft 100 rotates, the ball elements 110 roll to the deep ends of the opposing recesses in the plates 106 and 108 40 permitting the thrust plate 94 to move axially to the right as viewed in FIGURE 5. The rotary movement of the shaft 100 also tightens the spring 126. Upon subsequent reduction of fluid pressure, the spring 126 rotates the shaft 100 in reverse resetting the rotary conversion mechanism and expelling fluid from the receiving chamber located between the diaphragm 90 and the cap 86.

It will be observed that throughout the operation of the rotary actuator the thrust bearing elements 116 are under compression either by force of the fluid pressure or by force of the spring 126. This being the case, it is not necessary to cage the thrust bearing elements. However, these elements are retained in a circular configuration with an annular groove 134 disposed in the spacer plate 118.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

65 The invention having been thus described, the following is claimed:

1. In a fluid powered actuator device for imparting 70 rotary movement to a shaft, a housing, a flexible diaphragm partitioning said housing into two chambers, means providing a fluid inlet to one of said chambers, a thrust plate positioned for sliding movement in the other chamber adjacent said diaphragm, said thrust plate having a periphery interfitting the periphery of said other chamber so as to contain said diaphragm, a shaft passing

centrally through said other chamber normal to said diaphragm and having one end supported for rotation in said thrust plate, a pair of adjacent annular plates encircling said shaft in said other chamber between said thrust plate and the opposite wall of said housing, the annular plate nearest said thrust plate having freedom for axial movement on said shaft, said plates having opposing inclined arcuate surfaces, a roller element interposed between said plates and coacting with their opposing surfaces to impart relative rotation thereto upon movement of said axially movable plate toward the other plate, means securing said axially movable plate against rotation relative to said shaft and means securing the other annular plate against rotation relative to said housing, and means providing a thrust bearing between said thrust plate and said nearest annular plate whereby rotation of the latter is not transmitted to the former.

2. The device according to claim 1 including yielding means operating between said thrust plate and the nearest annular plate to preload the roller element between the 20 annular plates.
